UNITED STATES PATENT OFFICE.

MEYER BAYUK, OF JENKINTOWN, PENNSYLVANIA, ASSIGNOR TO BAYUK CIGARS INCORPORATED, OF PHILADELPHIA, PENNSYLVANIA, A CORPORATION OF MARYLAND.

CIGAR-BUNCH MACHINE.

Application filed February 7, 1925. Serial No. 7,480.

To all whom it may concern:

Be it known that I, MEYER BAYUK, a citizen of the United States, residing at Jenkintown, county of Montgomery, and 5 State of Pennsylvania, have invented a new and useful Improvement in Cigar-Bunch Machines, of which the following is a full, clear, and exact description, reference being had to the accompanying drawings, which 10 form a part of this specification.

My invention relates to an improvement in automatic cigar bunch machines, and more particularly to an improved form of crimpler for cigar bunch machines of the automatic type.

Heretofore cigar bunch machines adapted for the production of cigar bunches have been known and have proved satisfactory to a substantial degree. However, such machines have heretofore been usable, from the practical and commercial standpoints of the cigar manufacturers, only on cigars of relatively low selling price, since the bunches produced are not, even if hand-wrapped, of 20 such a character of workmanship as to recommend them to the consumer of relatively expensive cigars.

Such automatic bunch machines as have heretofore been put into practical use have 30 comprised an organization of devices for bringing together a filler and a binder in a dampened condition and effecting the rolling of the binder and filler to form a bunch. The bunch formed is usually cylindrical in 35 shape, though the ends of the filler are usually cut out before rolling by suitable cutters, and where, as is usual, the completed cigar is desired to have a reduced end or ends, it is necessary to form the bunch into 40 substantially final shape while it is still damp and before the application of the wrapper. For this purpose there has been provided a device generally known as a crimpler, the bunch being passed through a 45 softening roll before entry into the crimpler for shaping.

A typical crimpler heretofore utilized 50 comprised a pair of jaws actuated by suitable mechanism to move toward each other and then in opposite directions one to the other at right angles to the direction of their initial movement toward each other. A cradle positioned between the jaws serves to support a bunch, the end portions of

which, when the jaws initially move toward each other, are flattened and, when the jaws move oppositely at right angles to the direction of their initial movement, are subjected to a right-angled pressure and pressed to final shape. The ends of the jaws 60 being provided with desirably shaped surfaces so that when the jaws are finally closed, the end portions of the bunch will be pressed into the desired shape.

Such crimplers are open to various objections, but principally in that, as a result of the distinct pressures, at right angles to one another, to which the bunch is subjected successively, the filler is improperly distributed in the ends of the bunch, there is a 70 tendency to open the binder and the bunch has a very distinct "machine made" appearance as opposed to the desirable hand-made appearance.

Now it is the object of my invention to 75 provide a crimpler which will enable the production of a superior bunch, in which the desirable distribution of the filler will not be disturbed and which will enable the production of a cigar having a hand-made 80 appearance.

Further objects of my invention are to provide a crimpler of such a nature as will obviate the necessity for passing the bunch through a softening roll before crimping 85 and a crimpler, which will operate with equal efficiency upon bunches of such variations in size as may result, for example, from variations in the amount of filler fed to the rolling device, or from stretching of 90 the rolling apron.

Still further objects of my invention are to provide a crimpler which may operate on substantially the whole length of a cigar and one which will be of a high degree of 95 efficiency and durability in operation and relatively simple of adjustment.

Having now indicated, in a general way, the nature and purpose of my invention, I will proceed to a detailed description thereof, with reference to the accompanying drawings, in which I have illustrated a preferred embodiment, and in which—

Fig. 1 is an elevation of a portion of a cigar bunch machine embodying my improved crimping mechanism.

Fig. 2 is an enlarged detail section through the crimpers on line 2—2 of Fig. 3.

Fig. 3 is a similar view at right angles thereto taken on line 3—3 Fig. 2.

Fig. 4 is a plan view.

Fig. 5 is a horizontal section on line 5—5
5 Fig. 3.

Fig. 6 is a diagrammatic view of the crimpler jaws in an open relation.

Fig. 7 is an end view of the crimpler jaws in closed relation.

- 10 In the several drawings, *a* indicates the main frame of a cigar bunch machine and serves to support the various devices for forming the bunch and their driving mechanism. Upon a stand *b* is fixedly mounted
15 a bracket member *c* for supporting a jaw member *e*. Stand *b* also carries a slidably mounted bracket member *c'*, guided by means of guide members *d* and supporting a jaw member *e'*.
20 The jaws *e* and *e'* are complementary and oppositely disposed and present transversely extending bevel surfaces leading toward the back of each jaw, as shown in Fig. 6. The jaws longitudinally are shaped to the
25 desired shape of the finished bunch so that as the two jaws are brought together a bunch confined thereby will be gradually reduced, by rolling between the jaws, from its original substantially cylindrical shape to de-
30 sired final shape. The jaws *e*, *e'* are each composed of three sections, as shown in Fig. 4.

Positioned between the jaws *e* and *e'* is a platform *f* slidably supported on a pair
35 of rods *g* fixed in and extending from the fixed bracket member *c'*. The platform *f* serves to support a cradle *h* into which a bunch to be crimped is deposited by a transfer device *i*. A rod *j* is secured to the platform *f* and extends through an aperture in the bracket *c*, its free end being provided
40 with a collar *k* through which it is connected to a lever *l* pivotally mounted on a hanger *m* secured to bracket *c*. The free end of lever *l* passes through a slot in one end of a rod *n* secured to the slidable bracket *c'*. The members forming the jaws *e* and *e'* are transversely spaced as at *o* to permit them to clear the cradle when closed. Through
45 lever *l*, as shown in Fig. 3, it will be observed that as the jaws are brought together through the movement of bracket *c'* and jaw *e'* toward jaw *e*, causing the bunch to be rolled toward jaw *e*, the cradle will be moved toward jaw *e* and will not interfere with the manipulation of the bunch by the jaws. The slots *o* in the jaws into which the cradle passes permits them to be brought together without interference with the
55 cradle.

60 The movable jaw member *e'* is moved toward and into crimping relation with the complementary fixed jaw member *e* by means of a lever *p* pivotally mounted intermediate its ends on a hanger *q* carried by

frame *a*. One end of the lever operates the slidable bracket *c'*, supporting jaw member *e'*, by being directly entered in a slot therein, as shown in Fig. 3. The other end of the lever is connected to one end of a rod *r*
70 through an adjustable spring *s*, the free end of the rod operates a cam follower *t* adapted to follow a cam surface on a cam disc *u*.

It will now be observed that if the cam disc *u* be rotated the rod *r* will be reciprocated, resulting in oscillation of lever *p* and reciprocation of jaw member *e'* toward and away from jaw *e*. When a bunch is confined between the jaws a certain amount of resistance is presented to the final closing of the jaws and it is necessary to complete the crimping of the bunch to bring the jaws into final position in such a manner as to set the bunch to shape. This is accomplished through the medium of spring *s*, the cam surface being so cut as to tend to bring the jaws sharply to final position.

Adjacent the ends of the jaws *e* and *e'* are suitably mounted and actuated locaters *v*, adapted, when a bunch is deposited in the cradle *h* by the transfer *i*, to locate it properly lengthwise in relation to the jaws.

Positioned adjacent the ends of the jaws are suitably operated knives *w* which are adapted to be actuated when the jaws are fully closed to trim the ends of the bunch.

From the above description, the operation of the crimpler, will, it is believed, be clear. However, it should be noted that as the jaw *e'* is moved toward the jaw *e* after engaging a bunch, supported in cradle *h*, the bunch is rolled between the jaws and simultaneously softened and gradually reduced in size and shape until the jaws reach their closed position when the bunch is set in final shape. During the rolling of the bunch, it is under the control of the cradle, which, as has been disclosed, is moved with the bunch toward the fixed jaw *e*, and prevents the bunch from turning out of line during the rolling.

It will be noted that the crimpler in accordance with my invention acts upon the full length of the bunch preventing the formation of stem holes by avoiding bulging of any part of the bunch when pressure is applied and by crushing the stems in the filler.

It will be further noted that the crimpler shapes the bunch by rolling it to final shape, which serves to distribute the filler, avoids distortion of the filler and binder, prevents unwrapping of the binder, and results in the production of a superior bunch.

Having now fully described my invention, what I claim and desire to protect by Letters Patent is:

1. A crimpler for cigar bunch machines comprising, in combination, a pair of jaws
130

and means to effect a relative movement of said jaws, said jaws being complementary and so shaped as to, when relatively moved, roll a bunch between them and gradually 5 reduce it to a final desired shape.

2. A crimper for cigar bunch machines comprising, in combination, a pair of jaws adapted when closed to enclose a longitudinally extending space having the desired 10 shape of a bunch, said jaws being provided with transversely extending bevelled surfaces, means to position a bunch between said bevelled surfaces of said jaws, and means to move one of said jaws relative to 15 the other, whereby said bunch will be gradually rolled and reduced to desired shape.

3. A crimper for cigar bunch machines comprising, in combination, a pair of jaws, said jaws being complementary and shaped 20 transversely and longitudinally to effect, on relative movement in parallel planes, the gradual reduction of a bunch to a desired shape by rolling, means to position a bunch between said jaws, and means for moving 25 one of said jaws relatively to the other in a single plane.

4. A crimper for cigar bunch machines comprising, in combination, a pair of jaws, said jaws being complementary and shaped

transversely and longitudinally to effect, on 30 relative movement in parallel planes, the gradual reduction of a bunch to a desired shape by rolling, means for the support of a bunch between said jaws, means to move one of said jaws relative to the other, and 35 means to move said supporting means to maintain its relative position on movement of said jaw.

5. A crimper for cigar bunch machines comprising, in combination, a pair of jaws, 40 said jaws being complementary and shaped transversely and longitudinally to effect, on relative movement in parallel planes, the gradual reduction of a bunch to a desired 45 shape by rolling, a cradle positioned between said jaws for the support of a bunch, means to move one of said jaws relative to the other, means actuated by said movable jaw adapted to move said cradle on movement of said jaw whereby the relative position of said cradle to said jaws will remain 50 substantially the same during movement of said jaw.

In testimony of which invention, I have hereunto set my hand, at Philadelphia, 55 Pennsylvania, on this 21st day of January, 1925.

MEYER BAYUK.
